UNITED STATES PATENT OFFICE.

JAMES HARRIS HARDY, OF CRAWFORD, MISSISSIPPI.

RAILWAY CROSSING.

1,425,472.

Specification of Letters Patent. Patented Aug. 8, 1922.

Application filed October 25, 1921. Serial No. 510,273.

To all whom it may concern:

Be it known that I, JAMES HARRIS HARDY, resident of Crawford, in the county of Lowndes and State of Mississippi, and a citizen of the United States, have invented certain new and useful Improvements in Railway Crossings, of which the following is a specification.

This invention relates to a railway crossing, and has for its object to provide a readily operable mechanism, wherein there is presented a continuous set of rails for traffic moving in a given direction, the rails of the opposite set of rails so constructed as to be moved laterally by the energy of the moving train to afford a sufficient clearance for the flanges of the wheels thereof.

In the accompanying drawings:

Fig. 1 is a plan view of the crossing.

Fig. 2 is a similar view thereof showing certain parts moved to give a clear track in one direction.

Fig. 3 is a detail view of one of the guard rail sections.

The numeral 1 designates a supporting bed arranged at the intersection of the main line rails 2—2 and 3—3 which intersect at right angles to each other. Arranged upon the base in alignment with the set of main line rails 2—2 are a set of rail sections 4—4, while a similar set of rail sections 5—5 are arranged in alignment with the main line rail sections 3—3. These rail sections 4—4 and 5—5 are tapered as at 6 at their ends.

At each corner of the intersected main line rail is arranged a guard rail section, preferably consisting of forwardly extending members 7 and 8 which are at right angles to each other and adapted to lie parallel with the inner sides of the main line sections 2—2 and 3—3. The outer ends of these members 7 and 8 are adapted to turn inwardly from the main line rails for a purpose hereinafter set forth. Numerals

9 and 10 indicate inwardly extending members which are adapted to lie parallel with the inside rail sections 4 and 5, these members being tapered toward the outer end thereof and adapted at all times to be in the space with respect to the rail sections 4 and 5.

The members 7 and 9 Fig. 1 are spaced as at 11 and the members 8 and 10 are spaced as at 12 to provide clearance space for the flanges of the wheels. These members 7—8—9 and 10 are integral with a base 13 and move as one when actuated as hereinafter

explained. The forwardly extending members 7 and 8 are each provided with laterally extending members 14 and 15, the member 14 as disclosed in Fig. 1 being aligned with the rail section 5 having its outer end tapered as at 16 to coincide with the tapered end of the rail section 5, the member 15 being tapered as at 17 to coincide with the tapered ends of the rail section 4—4.

As disclosed in Fig. 1, traffic is permissible upon the main line rails 3—3, the guard rails being resiliently held in that position by means of a bar 18 pivoted as at 19 to the base 1, the outer end thereof being pivotally connected as at 19 to the base 13 of the guard rail members. The numeral 20 indicates a rod pivoted as at 21 to the base 1, the inner end thereof being slidably received upon the outer end of the bar 18. Received upon the rod 20 are cup members 22 and held there between upon the rod 20 is a tension spring 23. The numeral 24 indicates stop members which are adapted to limit the movement of the guard rail sections 9 and 10 in one direction.

As illustrated in Fig. 1, the guard rails are in a position to permit traffic on the main line rails 3—3, the inner ends of the guard rails 10 lie parallel with the main line rails 3—3 abutting the stop member 24, while the inner ends of the guard rail 9 lie close to the rail sections 4—4 and in space relative to the stop member 24, the bars 18 and the rods 20 being off center and held in this position by the tension springs 23. The laterally extending members 14 of the guard rail sections 7 are aligned with the main line rails 3—3 and the rail sections 5—5 thereby form a continuous rail for traffic moving in that direction. When the traffic is resumed on the main line rail sections 2—2 the flanges of the wheels of the moving train strike the ends of the guard rail sections 7—7 in approaching the crossing causing the guard rail sections to be moved longitudinally and laterally with respect to the main line rails 2—2, the laterally extending members 14—14 of the guard rail sections 7 traveling along the tapered portion of the rail sections 5—5 while the inner ends of the guard rail sections 9—9 move toward the abutment 24, the inner ends 10—10 of the guard rail simultaneously move laterally toward each other, this action causing the lateral extending members 15 of guard rails 8—8 to assume

100
105
110

aligned position with the main line rails 2—2 and rail sections 4—4 presenting a continuous rail for traffic in this direction being held in this position by the spring-actuated 5 bar 18.

I claim:

1. A railroad crossing, each rail including a stationary section, longitudinal movable guard rail sections comprising arms, one of 10 which is resiliently held against one of the rail sections while the other arm is resiliently held in spaced relation with the oppositely disposed rail sections, said guard rail sections adapted to be moved laterally 15 and longitudinally by the wheels of the moving train.

2. In a railroad crossing, each rail including a central stationary section having tapering ends, divided laterally and longitudinally movable guard rail sections arranged parallel with the stationary rail sections and provided at each end with tapering members adapted to align with the ends 25 of the oppositely disposed rail sections, resilient means normally holding said divided guard rail sections against longitudinal and lateral movement, the ends of the divided guard rail sections being spaced from the guard rail and rail sections and adapted to 30 be engaged by the flanges of the wheels of the moving train whereby the guard rail sections move both laterally and longitudinally to effect a clearance space between them and the main line rails and the stationary rail sections.

3. In a railroad crossing, each rail including a central stationary section having tapering ends, divided laterally and longitudinally movable guard rail sections arranged at the intersections of the main line 40 sections, said guard rail sections being provided with laterally extending attached members adapted to be moved into alignment with the tapered ends of the stationary rail sections, resilient means normally 45

holding said guard rails against lateral and longitudinal movement, said guard-rail sections adapted to be operated by the moving train whereby the guard rail sections are moved both laterally and longitudinally to 50 provide passage way for the wheels of the moving train.

4. In a railroad crossing, each rail including a central stationary section having tapering ends, guard rail sections arranged 55 at the intersection of the main line rails said guard rail sections comprising a base arranged beneath the rails and having forwardly and rearwardly projecting guard rails projecting therefrom in parallel with 60 the main line rails and rail sections, the inner ends of said guard rail sections being bent inwardly from the main line rails, members extending laterally from the guard rails and adapted to be alternately aligned 65 with the main line rails and stationary rail sections, abutments adapted to be laterally engaged by the inner ends of the guard rail sections, resilient means for normally holding each of said guard rail sections against 70 longitudinal and lateral movement, said guard-rail sections cooperating with the moving train whereby each of the guard rail sections is moved both longitudinally and laterally to align the laterally extending 75 members thereof with the main line rails and to provide a passage way for the wheels of the moving train.

5. A railroad crossing including intersecting main line rails, guard rails at each 80 main line rail intersection, movably supported guard rail sections, and resilient toggle means connected with the movable guard-rails for automatically throwing and locking the latter in one position or another according to the direction in which the joint of the toggle passes its dead center. 85

In testimony whereof I hereunto affix my signature.

JAMES HARRIS HARDY.
